DOW B. HUGHES, OF NEW YORK, N. Y., ASSIGNOR TO THE CITIZENS SAVINGS AND TRUST COMPANY, OF CLEVELAND, OHIO, A CORPORATION OF OHIO, TRUSTEE.

MAGNETO.

1,143,119.

Specification of Letters Patent. Patented June 15, 1915.

Application filed May 10, 1912. Serial No. 696,337.

To all whom it may concern:

Be it known that I, Dow B. HUGHES, a citizen of the United States, residing at New York, in the county of New York and State of New York, have invented a certain new and useful Improvement in Magnetos, of which the following is a full, clear, and exact description.

This invention relates to magnetos and 10 has for its object to provide a magneto construction which has high efficiency; which is strong mechanically; which is comparatively inexpensive to manufacture; and which is easy to assemble or disassemble.

15 The invention may be briefly summarized as consisting in certain novel details of construction and combinations and arrangements of parts which will be described in the specification and set forth in the appended claims.

20 In the drawings wherein I have shown the preferred embodiment of my invention, Figure 1 is a longitudinal vertical sectional view of the magneto with parts in elevation 25 and parts broken away; Fig. 2 is an end view; and Fig. 3 is a detail view showing particularly the construction of the combined brush holding arm and connector between the armature winding and transformer.

25 Referring now to the drawings, 9 represents the field magnets and 10 the armature having at its ends shaft extensions 11 and 12 which are mounted in bearings 13 and 14 supported respectively by the end plate 15 and gear case 16.

30 One end of the armature winding is grounded and the other is connected by a conductor (not shown) to an insulated collector ring 17 which is supported by the shaft extension 11 between the bearing 13 and the armature. A cylindrical extension 15^a of the end plate 15 projects over and around the collector ring, as shown.

35 On the shaft extension 12 between the bearing 14 and the armature is secured a gear 18 which meshes with a larger gear 19 which is secured to a tubular bearing or bushing 20 journaled in a second end plate 21. Secured to the gear 19 is the rotary distributor member 22 in the form of an insulating support carrying a rotary contact 23 which is electrically connected to a contact disk 24 consisting in this case of the head of a screw located at the center of the rotary

support 22. This contact disk or head is located on the inner side of the support 22 (for a purpose to be explained) and the screw has a shank extending outwardly and provided on its outer end with a clamping unit 24^a. The rotary contact is adapted to successively engage the stationary contacts 25 secured to a distributor case 26 which in turn is secured to the gear case 16.

Beneath the distributor is the circuit breaker, the parts of which are inclosed within a cylindrical casing 27. The circuit breaker includes a cam 28 having a hollow shank extending into the shaft extension 12 which is hollow as shown. The cam is secured in place by a screw 29 having a long shank extending through the cam shaft and the shaft extension 13 into a threaded opening of the adjacent end plate of the armature. A washer 30 is placed between the head of the cam 28 and the inner ring of bearing 14, and a second washer 31 is placed between the bearing ring and the gear 18. By tightening the screw 29, not only is the cam secured in position, but the washers referred to and the inner ring of bearing 14 are firmly clamped between the cam and the gear 18, and at the same time the bearing 14 is caused to serve as a thrust bearing to eliminate all end play of the armature. This latter result is accomplished when the screw 29 is tightened by giving the outer ring of bearing 14 a tight fit in its support, while the inner ring of the bearing 14 has a loose fit on shaft extension 12, and by giving the inner ring of bearing 13 a tight fit on shaft extension 11 and the outer ring of this bearing a loose fit on its support 15^a.

35 In this application I am not claiming any features of the distributor or of the circuit breaker except those which enter into combination with and directly coöperate with other parts of the magneto structure.

40 In the space between the top of the magnets and the armature, I place a cylinder 32 containing a transformer and preferably also a condenser. This cylinder is slipped into a recess provided for it and has a bearing at one end in end plate 15 and in its opposite end in a cylindrical shoulder of end plate 21. This cylinder includes an inner cylindrical wall of insulating material, an outer metal wall or casing 32^a, and inner and outer ends 32^b and 32^c. The metal casing which is provided for the pur-

pose of giving the necessary strength and rigidity to the cylinder has openings 32^a formed in its cylindrical wall, so that said casing will not constitute a closed secondary, as would otherwise be the case if the cylindrical wall were not interrupted by said openings.

One terminal of the transformer is connected to the head of a screw 33 which is secured in the center of the outer end 32^c of cylinder 32, and which has a threaded shank projecting outwardly through said end beyond the end plate 15. Another terminal 34 of the transformer extends through 15 an insulating supporting arm 35 which is secured in the inner cylinder head 32^d, and projects through bearing bushing 20 for gear 19 into proximity with the contact disk 24 of the distributor. The outer end of the 20 arm 35 contains a spring pressed brush 36 which is electrically connected to the terminal 34 and at its outer end bears against the contact disk 24.

Between the collector ring 17 and transformer cylinder, I provide the following connecting and locking means. On the cylindrical extension 15^a of the end plate 15 is fitted a ring or band 37, which is adapted to be turned on said extension for a purpose to be explained. The ring 37 is provided with a hub or tubular boss in which is seated a rigid arm 38, having at its inner end a spring pressed brush 39, which bears upon the collector ring 17. The inner portion of the arm 38 extends through an elongated slot 15^b of the extension 15 so that the ring and arm may be turned through a suitable arc. At the upper end of the arm 38 is a head 40 having an open slot 40^a, which receives the threaded shank of the screw 33, when said arm 38 is swung upwardly to upright position, as shown by full lines in Fig. 2. This head has on one side a cup or recess 40^b which is adapted to receive a clamping nut 41 on the threaded shank of screw 33. When this nut is screwed into the recess, the arm 38 is prevented from turning from the upright position, and at the same time the head 40 of the arm is electrically connected to the threaded shank of the screw. A second nut 42 is also provided on the shank of the screw, to serve as a lock nut and as a binding-post nut, inasmuch as a conductor extending to the circuit breaker 55 is adapted to be clamped between the two nuts.

It will be seen from the above description that when the transformer cylinder is slipped into position, one terminal of the transformer is connected to the distributor by the engagement of the brush 36, with the central contact disk of the rotating part of the distributor. Furthermore, when the arm 38 is swung upwardly to upright position and locked in the manner above de-

scribed to the outwardly projecting terminal of the transformer or threaded shank of the screw 33, the collector ring 17 of the magneto,—or in other words,—the magneto armature, is electrically connected in the proper manner to the transformer, and at the same time, the transformer cylinder is locked against outward movement, and the arm 38 and brush 39 carried thereby are held in proper position with reference to the collector ring.

When it is desired to remove the transformer cylinder, all that it is necessary to do is to loosen the nuts 41 and 42, and swing the arm 38 to the position shown by dotted lines in Fig. 2. The cylinder can then be slid outward from its normal position.

I thus provide a rigid connecting and locking means which is very effective for both purposes, and is far more effective than would be the case if I employed a separate holder for a brush, a separate locking means for the transformer cylinder, and a flexible connection between the brush and transformer terminal.

Having thus described my invention, what I claim is:

1. A magneto comprising horse-shoe magnets, an armature having shaft extensions, a distributor, a pair of gears for driving the distributor including a gear on one of the shaft extensions, and a second gear meshing therewith, a tubular bearing for said second gear, said distributor comprising a rotating part movable with said second gear and provided in line with the axis of said tubular bearing with a contact member, a transformer casing mounted within the upper part of the magnets above the armature, said casing having at its inner end an arm projecting outwardly through said tubular bearing, and provided at its end with a brush engaging the contact member of the rotating part of the distributor.

2. A magneto comprising a magnet, an armature, a transformer supported in the magnet adjacent the armature and provided with an outwardly projecting terminal, a member electrically connected to the armature and adapted to be connected to said terminal, and a support for said member which permits the latter to be turned toward and from the terminal.

3. A magneto comprising a field magnet, an armature, a transformer supported in the magnet adjacent the armature and having an outwardly projecting terminal, an arm adapted to be connected at one end to said terminal, a support for said arm which permits the latter to be turned toward and away from the terminal, and current collecting means comprising a ring and a brush, one movable with the armature and the other carried by said arm.

4. A magneto comprising a horse-shoe

field magnet, an armature with supporting shaft extensions, a collector ring on one of said shaft extensions, a transformer casing supported in the magnet above the armature and having an outwardly projecting terminal, and a combined brush holder and connector extending between the collector ring and said terminal.

5. A magneto comprising a horse-shoe field magnet, an armature with supporting shaft extensions, a collector ring on one of said shaft extensions, a transformer casing supported in the magnet above the armature and having an outwardly projecting terminal, and a rigid arm adapted to be connected at its upper end to said terminal and at its inner end having a brush engaging the collector ring.

6. A magneto comprising a horse-shoe field magnet, an armature with supporting shaft extensions, a collector ring on one of said shaft extensions, a transformer casing supported in the magnet adjacent the armature and having an outwardly projecting terminal, and a combined brush holder, connector and lock for the transformer casing, comprising a rigid arm extending outwardly with respect to the collector ring and adapted to be secured at its upper end to said terminal.

7. A magneto comprising a field magnet, an armature, a collector ring rotatable with the armature, a transformer casing supported above the armature, and having an outwardly projecting terminal, an arm having a brush at its lower end engaging the collector ring and at its upper end having means for engaging said terminal, and a support for said arm arranged concentri-

cally with respect to the axis of the armature and adapted to be turned to swing the upper end of said arm toward or away from said terminal.

8. In a magneto, a magneto frame including field magnets and end plates, an armature supported by said frame and having a collector ring, a transformer casing removably secured in said frame above the armature and having an outwardly projecting terminal, a rigid arm having at its lower end a brush engaging the collector ring and having at its upper end means for engaging said terminal, a ring constituting a support for said arm swiveled to said frame concentrically with respect to the axis of the armature, whereby said arm may be turned to an upright position or may be swung away from said terminal to permit the removal of said transformer casing.

9. In a magneto, field magnets, an armature having a hollow shaft extension, a cam having a hollow shank extending into said shaft extension, a gear on said shaft extension, a bearing ring for the armature on said shaft extension between the cam and the gear, and a screw extending axially of said shaft extension through the shank of the cam for securing the cam in position and for clamping the bearing between the cam and the gear.

In testimony whereof, I hereunto affix my signature in the presence of two witnesses.

DOW B. HUGHES.
